UNITED STATES PATENT OFFICE.

GEORGE COWDERY AND EDWIN ROBINS THOMAS, OF SYDNEY, NEW SOUTH WALES, AUSTRALIA.

RAIL FOR RAILWAYS AND TRAMWAYS.

SPECIFICATION forming part of Letters Patent No. 289,626, dated December 4, 1883.

Application filed August 9, 1883. (No model.) Patented in England April 11, 1883, No. 1,825, and in New South Wales May 26, 1883, No. 1,243.

To all whom it may concern:

Be it known that we, GEORGE COWDERY and EDWIN ROBINS THOMAS, subjects of the Queen of Great Britain, residing at Sydney, 5 in the Colony of New South Wales, Australia, have invented a new and useful Rail for Railways and Tramways, (for which we have obtained Letters of Registration in New South Wales, No. 1,243, bearing date May 26, 1883, 10 and a patent in Great Britain, No. 1,825, and bearing date April 11, 1883,) of which the following is a specification.

Our invention relates to an improved rail for railways and tramways, built up or constructed of two similar sections, giving four perfect and independent flanges to work upon; and the objects of our improvements are to give a longer life to the track, combined with great economy of metal for the required 20 strength, the weight of the fastenings being also much less than for rails in ordinary use. We obtain these objects by the construction and combination illustrated upon the accompanying sheet of drawings, in which—

25 Figure 1 is an elevation of part of a track with our improved rail; Fig. 2, a plan of same, the letter F indicating joint of top rail and center of bottom rail; and Fig. 3 is a transverse section at C D, Figs. 1 and 2, drawn to 30 an enlarged scale.

Our rail complete consists in the combination of two separate sections or rails, A A, of the same transverse section, as shown on the drawings. The two sections or rails are to be 35 placed or built together to form one rail. The two rails or sections which combined form "the rail," having the same transverse section, can be turned over laterally, or end for end, and either be made to take the place or position 40 of the other, thus giving in each change of position a fresh working surface or "tread," this combination having the advantage of a four-headed rail. The rails are to be seated at intervals in chairs placed upon sleepers, and the 45 chairs pinned to the sleepers in the ordinary manner. The chairs are to be of the form shown, or of a similar form to that shown in the drawings, according to the sizes and weights of the rails to be used. At given

spaces the two sections of the rail are to be 50 fixed together by pins or bolts B. These pins or bolts pass through elongated holes in each section of the rail, as shown in the drawings at E E. While placing these pins or bolts in position the rails or sections must be sprung to 55 ward each other by means of a cramp for this purpose. When the pins or bolts are in position and the cramp released, the shoulder under the head of the pin fits into the elongated hole tightly, preventing any possibility of the 60 pin turning or altering its position, thus forming a perfect tie or fastening. The pins or bolts cannot be displaced except by the use of the cramp, and the tendency of the load upon 65 the rails is to tighten the pins. By this combination a break of joint can be secured (see drawings at F) without the use of fish-plates, screw-bolts, and nuts, and without reducing the strength or efficiency of the rail in any respect. With this combination rail the use of 70 keys in the chairs is entirely superseded, as the lower flanges of the sections A A of rail fix 75 tightly under the lips a of the chairs, but do not rest on the chairs, thus preventing any possibility of wear on the faces of the flanges previous to their being turned. However, in 80 some instances, it may be deemed advisable to use a pin or bolt, B, at the chairs, for which provision has been made, as shown in Fig. 3 of the drawings. The rolling weight or load is 85 sustained entirely by a center piece in the chair on which the upper flanges rest. (See drawings at G, Fig. 3.)

Among the advantages of the above-specified rail are that it combines all the best features 85 of the Barlow rail, the double-headed rail, the bridge-rail, and rail of the contractor's pattern; the distribution of metal in each section will allow of their being well and soundly 90 rolled; there will be less weight per lineal yard to sustain an equal load; it presents four new and independent flanges to work over, giving, as aforesaid, a long life to the rail; fish-plates, screw-bolts, and nuts are not required for fixing; it gives break of joint 95 without weakness; wooden keys are dispensed with; the laying, relaying, or shifting is effected with rapidity; considerably less weight

in rails per lineal yard for equal loads than required in ordinary rails. The lower section could be used as a permanent foundation, (and, if considered more economical,) of tougher metal, and the upper section of steel, which alone need be shifted or renewed.

The points, crossings, and switches may be similar to those at present used.

What we claim as our invention, and desire to secure by Letters Patent, is—

1. A rail formed of the two sections A A, having similar top and bottom flanges, A' A', forming four perfect and independent flanges, the top flanges overlapping when the two parts are combined to form a rail, substantially as shown and described.

2. A rail formed of the two sections A A, the pin or bolt B passing through the elongated holes E E, and fixing the two sections of the rail, in the manner substantially as described.

3. The combination of a rail formed of the two sections A A, fixed by the pin or bolt B or other suitable fastening, and a chair having the center piece, G, and the lips a, substantially as and for the purposes specified.

GEORGE COWDERY.
EDWIN ROBINS THOMAS.
